2 SHEETS—SHEET 2.

UNITED STATES PATENT OFFICE.

WILLIAM W. FARNSWORTH, OF LITTLETON, COLORADO.

RENOVATOR.

1,281,925.

Specification of Letters Patent.

Patented Oct. 15, 1918.

Application filed January 21, 1918. Serial No. 212,859.

To all whom it may concern:

Be it known that I, WILLIAM W. FARNSWORTH, a citizen of the United States, residing at Littleton, in the county of Arapahoe and State of Colorado, have invented certain new and useful Improvements in Renovators, of which the following is a specification.

This invention relates in general to improvements in renovators, but more specifically to improved means whereby the dust or foreign matter may be dislodged or agitated by means of a blast of air and which blast serves the further function of conveying away the agitated dirt or foreign matter.

A further object is to provide an improved device of this character in which the dust or foreign matter is disturbed by a blast of air and which device is provided with means whereby the dust laden air will be clarified and the clarified air used over and over again.

A further object is to provide an improved device of this character which will be of a simple, durable and compact structure and effective and efficient operation.

To the attainment of these ends and the accomplishment of other new and useful objects as will appear, the invention consists in the features of novelty in substantially the construction, combination and arrangement of the several parts, hereinafter more fully described and claimed and shown in the accompanying drawing, illustrating this invention and in which;

Figure 1 is a view partly in side elevation and partly in vertical longitudinal section, of an improved device of this character, constructed in accordance with the principles of this invention.

Fig. 2 is a top plan view of Fig. 1 with parts in section and with parts broken away.

Referring more particularly to the drawings, the numeral 10 designates generally a cleaning head having an inlet opening 11, adapted to be moved over the surface to be cleaned. The head may be of any desired size and configuration and is provided with a discharge outlet opening 12.

50 A blast creating device 13, preferably in the form of a fan is arranged within a chamber 14 and this chamber has communication with the head through the opening 15.

55 The blast creating device 13 is operated in any desired or suitable manner, preferably

by means of a motor 16, and which motor receives its energy from any suitable source, and is preferably of the electric type. Arranged within the head 10 and preferably adjacent the opening 11 is a casing or chamber 17 of any desired size and configuration, but is preferably of a length to extend substantially across the opening 11. This chamber is supported in any desired or suitable manner and is provided with one or more series of openings 18 preferably in the bottom thereof, which form communication between the interior of the chamber 17 and the head 10, and these openings 18 are preferably arranged at an angle with respect to the surface over which the opening 11 passes. Connected with the chamber 17 in any desired or suitable manner, preferably adjacent the ends thereof, are blast or inlet pipes 19, and the free extremities of these pipes 19 are connected as at 20 with a sack or bag 21, which latter is fluid tight. Arranged within the sack 21 is another sack or casing 22, and the latter is constructed of porous material and of a size preferably somewhat smaller than the sack 21. This sack 22 is connected with the discharge outlet opening 12 of the cleaning head, and the end of this sack 22 may be detachably secured in position in any suitable manner, such as by means of fastening devices 23, while the portions of the sack 21 may be removable secured to the tubes or pipes 19 in any suitable manner, such as by means of the fastening devices 24.

The casing 17 is preferably removably secured within the cleaning head, although it is of course to be understood that if desired, the casing may be formed therein during the course of manufacture. When the casing is removably held in position, any suitable means may be provided for thus holding it, such as the securing devices 25, which are adjustably mounted on a portion of the cleaning head and have engagement with the ends of the casing.

The casing 17 is also removably connected with the pipes 19 so that when it is desired to remove the casing, all that is necessary is to adjust the fastening devices and detach the casing from the pipes 19, when the casing may be readily removed.

In operation, the blast creating device 13 is set in operation and the blast of air created thereby will be discharged from the chamber 14 through the outlet opening 12

2
and into the sack or casing 23. This sack being of a porous material, the air will pass through the wall thereof into the sack or casing 21, and during such passage of the 5 air, it will be clarified by the removal of the dirt and foreign matter therefrom. The air blast having been discharged into the sack 21 will pass through the outlet portions 20 thereof into the pipes 19 and will be conveyed through these pipes into the casing 17 to be discharged therefrom through the 10 openings 18 at an angle to and against the surface to be renovated. This will not only dislodge the foreign particles from the 15 surface, but the air blast passing from the casing 17 operates as an agitator which effectively dislodges and removes the particles from the surface. The agitated foreign matter being confined within the cleaning 20 head 10 will be carried by the blast of air toward the opening 15 of the chamber 14, at which time the air currents will be caught by the blast creating device 13 to be removed from the cleaning head and then discharged 25 through the outlet opening 12 into the purifying or clarifying device. Thus it will be manifest that the same air can be used over and over again.

While there is shown two series of openings 30 18 in the bottom of the casing 17, it is of course, to be understood that both of these series of openings may not be necessary, and it is also to be understood that any desired number of openings may be provided.

What is claimed as new is:

1. A renovator embodying a cleaning head, a casing disposed within the cleaning head and having discharge outlets disposed to 40 direct a blast of air against the surface to be cleaned, a suction creating device within the cleaning head, a motor supported by the head for operating a suction-creating device, the intake of said suction creating device having communication with the interior of the head, and a conduit forming communication with the pressure side of the said suction device and the said casing.

2. A renovator embodying a cleaning head, a casing disposed within the cleaning head 50 and having discharge outlets disposed to direct a blast of air against the surface to be cleaned, a suction creating device within the cleaning head, a motor supported by the head for operating a suction-creating device, the intake of said suction creating device having communication with the interior of the head, and a separator through which the air currents pass before entering the said casing.

3. A renovator embodying a cleaning head, a casing disposed within and extending across the cleaning head and having discharge outlets disposed to direct a blast of air against the surface to be cleaned, means 65 for removably securing the casing within the head, a suction creating device within the cleaning head and having its intake in communication with the interior of the head, a conduit exterior of the head and forming 70 communication between the pressure side of the suction creating device and the said chamber, said chamber and conduit being detachably connected, and a motor supported by the head for actuating the suction creating device.

4. A renovator embodying a cleaning head, a casing disposed within and extending across the cleaning head and having discharge outlets disposed to direct a blast of air against the surface to be cleaned, means 80 for removably securing the casing within the head, a suction creating device within the cleaning head and having its intake in communication with the interior of the head, a motor supported by the head for actuating the suction creating device, a conduit forming communication between the pressure side of the suction creating device and the said 85 casing, and a separator through which the air currents pass before entering said casing.

In testimony whereof I have signed my name to this specification, on this 17th day of January, A. D. 1918.

WILLIAM W. FARNSWORTH.
